CONTAINER INSTRUMENT

Harry B. Chaffin, Canton, Ohio

Application September 30, 1939, Serial No. 297,412

1 Claim. (Cl. 46—175)

My invention relates generally to container instruments which may be used by individuals for carrying articles or materials from a source to a place remote from such source where the articles or materials may be used or consumed, and the container instrument being adapted for controlling or producing sound waves emitted or induced by the individuals using the container instruments.

In gatherings, in and out of doors, such as picnics, golf, baseball and football games, tennis, racing, swimming, hikes, riding, and the like, where individuals or spectators, many or few, congregate and cheer, call, yell or talk loud, their lips, throat, and vocal chords become strained and parched and dry.

By the use of megaphones, the cheering, yelling or calling is less strenuous and there is less strain on the lips, throat and vocal chords.

At such gatherings, horns are frequently used for producing noise with less strain on the throat and vocal chords than by yelling or cheering.

The location or seating of the spectators at such gatherings is such that liquids, foodstuffs, candy and other helpful articles are not usually immediately available.

On the other hand it is frequently awkward and inconvenient to carry and use in such public gatherings beverages and edibles in usual bottles, cans, and similar containers.

The objects of the present invention include the provision of an improved container instrument adapted for containing articles such as beverages and edibles and the like to a place of use, and also adapted for use as a megaphone, horn, or similar sound controlling or producing instrument.

Further objects of the present invention include the provision of an improved container instrument adapted for use as a container and a sound controlling or producing instrument and which is of simplified construction adapted for economical manufacture.

Further objects of the present invention include the provision of an improved container instrument adapted for use as a container and a sound controlling or producing instrument, and which is convenient and easy to use.

The foregoing and other objects are attained by the container instruments, constructions, parts, combinations, and sub-combinations comprising the present invention, the nature of which is set forth in the following general statement, preferred embodiments of which are set forth in the following description, and which

are particularly and distinctly pointed out and set forth in the appended claims forming part hereof.

The nature of the improved container instrument of the present invention may be stated in general terms as including a preferably conical tubular shell having a central opening extending therethrough and preferably being adapted in itself to amplify sound waves introduced into one end of the opening, other preferably removable walls or containers being associated with the shell to form therein one or more container compartments adapted for containing articles such as beverages and edibles and the like, each container compartment preferably having an access opening and a removable closure therefor.

By way of example a number of embodiments of the improved container instrument hereof are illustrated in the accompanying drawing forming part hereof, in which

Figure 1 is a longitudinal sectional view of a first embodiment of the improved container instrument hereof, as on line 1—1, Fig. 2;

Fig. 2, a transverse sectional view thereof as on line 2—2, Fig. 1;

Fig. 3, a longitudinal sectional view of a second embodiment of the improved container instrument hereof, as on line 3—3, Fig. 4;

Fig. 4, a transverse sectional view thereof as on line 4—4, Fig. 3;

Fig. 5, a longitudinal sectional view of a third embodiment of the improved container instrument hereof, as on line 5—5, Fig. 6;

Fig. 6, a transverse sectional view thereof as on line 6—6, Fig. 5;

Fig. 7, a longitudinal sectional view of a fourth embodiment of the improved container instrument hereof, as on line 7—7, Fig. 8;

Fig. 8, a transverse sectional view thereof as on line 8—8, Fig. 7;

Fig. 9, a longitudinal sectional view of a fifth embodiment of the improved container instrument hereof, as on line 9—9, Fig. 10;

Fig. 10, a transverse sectional view thereof as on line 10—10, Fig. 9; and

Fig. 11, an elevation view, with portions broken away and illustrated in section, of a sixth embodiment of the improved container instrument hereof.

Similar numerals refer to similar parts throughout the several views.

In Figs. 1 and 2, a first embodiment of the improved container instrument hereof is indicated generally by C—1 and includes a tubular

conical megaphone shell 12 preferably having a carrying handle 13 mounted on one side thereof.

Within the shell 12, walls form a preferably removable frusto-conical annular container indicated generally by 14, and which has an outer conical side wall 15 fitting against the inner conical surface of the shell 12, and an inner preferably conical side wall 16 and a smaller annular end wall 18 and a larger annular end wall 19.

The side walls and end walls of the container 14 form an annular compartment 20 for liquids.

Access is provided to the annular compartment 20 by means of registering side openings formed in the shell 12 and the container side wall 15, which registering access openings are provided with a closure member, as shown a cork 21.

The shell 12 has a smaller end opening 22 communicating with the smaller end opening 23 of the conical inner container walls 16, the larger end opening 24 of which communicates with the larger end opening 25 of the shell 12.

There is thus provided in the container instrument C-1 a megaphonic conical opening extending therethrough which is adapted for amplifying sound waves introduced by the user into the smaller end opening 22 of the shell 12, either before or after the liquid contained in the annular compartment 20 is partially or wholly removed.

In Figs. 3 and 4, a second embodiment of the improved container instrument hereof is indicated generally by C-2 and also includes a tubular conical megaphone shell 12 preferably having a carrying handle 13 mounted on one side thereof.

The shell 12 also has a smaller end opening 22 and a larger end opening 25. The smaller end opening 22 is provided with a removable disk closure wall 26 and the larger end opening 25 is provided with a removable disk closure wall 27 which may have a handle 28 attached thereto, and the wall 27 may have an access opening formed therein which may be provided with a closure member as shown a cork 29.

The shell 12 and the removable end closure walls 26 and 27 form a conical interior compartment 30 which may contain articles, such as edibles or liquids.

By first removing either the cork 29 or the larger end closure wall 27 the liquid or other articles contained in the compartment 30 may be removed. The smaller closure wall 26 is then removed, after which the megaphone shell 12 may be used as a megaphone in the usual way.

In Figs. 5 and 6, a third embodiment of the improved container instrument hereof is indicated generally by C-3, and also includes a tubular conical megaphone shell 12 preferably having a carrying handle 13 mounted on one side thereof, and a smaller end opening 22 and a larger end opening 25. Walls form a plurality of side by side longitudinally extending sectoral containers 31-c within the shell 12, each sectoral containers 31-c being formed as a preferably removable container having radial side walls 32 and a conical sectoral side wall 33 and a smaller sectoral end wall 34 and a larger sectoral end wall 35.

The radial side walls 32 abut against each other within the shell 12 and the conical sectoral side walls 33 abut against the inner surface of the conical shell 12.

Each smaller sectoral end wall 34 is provided

with a neck 36 having an access opening 37 therein and a removable closure cap 38 therefor. A removable closure cap 39 may also be provided for the larger end of the shell 22.

When the closure cap 39 and the containers 31-c are removed from the shell, the same may be used as a megaphone in the usual manner.

In Figs. 7 and 8, a fourth embodiment of the improved container instrument hereof is indicated generally by C-4, and also includes a tubular conical megaphone shell 12 preferably having a carrying handle 13 mounted on one side thereof, and a smaller end opening 22 and a larger end opening 25 and a closure cap 39 for the larger end opening.

Walls within the shell 12 form a plurality of sectoral annular containers 40-c and a central conical megaphone opening 41 extending through the length of the shell 12.

Each annular sectoral container 40-c is preferably formed as a removable annular sectoral container which is generally similar in construction to the removable containers 31-c, with the exception that walls of the containers 40-c form the central conical megaphone opening 41, so that when the cover 39 is removed the container instrument C-4 may be used as a megaphone without removing the containers 40-c.

In Figs. 9 and 10, a fifth embodiment of the improved container instrument hereof is indicated generally by C-5 and includes an annular conical shell wall 12 having a carrying handle 13 mounted on one side thereof and an inner conical wall 42, and a smaller annular end closure wall 43 and a larger annular end closure wall 44 forming an annular conical container compartment 45, there being an access opening provided in the outer conical shell wall 12 which has a closure member therefor as shown in the form of a cork 46. The inner conical wall 42 forms a megaphone passageway extending through the container instrument C-5 in which there may also be located a removable frusto-conical container indicated generally by 47. For retaining the removable frusto-conical container 47 in the inner conical wall 42 when the container instrument C-5 is being carried, a removable closure cap 39 may be provided for the larger end of the conical shell wall 12.

In Fig. 11, a sixth embodiment of the improved container instrument hereof is indicated generally by C-6 and includes a horn having a conical shell 48 with a usual sound producing reed mouthpiece indicated generally by 49 at its smaller end, and a closure cap 50 for its larger end, the conical shell 48 and the closure cap 50 forming a container compartment 51 in which articles may be located, which may be removed by removing the closure cap 50, after which the horn may be used in the usual manner.

Any desired preferably liquid-tight material or combination of materials may be utilized for the shells, compartment walls, and closures of the improved container instruments C-1, C-2, C-3, C-4, C-5, and C-6, such as metal, glass, paraffin impregnated cardboard, and the like.

The embodiments of the present improvements illustrated and described herein are by way of example and the scope of the present invention is not limited to the same or to the particular details thereof, but is commensurate with any and all novel subject matter contained herein, which may at any time properly under the patent laws be set forth in the claims hereof or originating herein, and the elements of any of

such claims are intended to include their functional or structural equivalents.

I claim:

A container instrument including a conical shell having opposite end openings and which in itself is adapted for use as a megaphone, and a plurality of removable containers having side

walls abutting each other and other side walls abutting the inner surface of the conical shell, and other side walls forming a central opening terminating in the opposite end openings of the shell.

5 HARRY B. CHAFFIN.
